UNITED STATES PATENT OFFICE.

LEWIS E. CURTIS, OF WARREN, OHIO, ASSIGNOR TO THE YOUNGSTOWN PRESSED STEEL COMPANY, OF WARREN, OHIO, A CORPORATION OF OHIO.

WALL TIE.

Application filed March 26, 1923. Serial No. 627,798.

To all whom it may concern:

Be it known that I, LEWIS E. CURTIS, a citizen of the United States, and resident of Warren, in the county of Trumbull and State of Ohio, have invented certain new and useful Improvements in Wall Ties, of which the following is a specification.

My present invention relates to improvements in wall ties such as are used for tying together inner and outer courses of bricks or blocks.

The invention aims to provide a construction which may be easily produced from a strip of sheet metal cut without waste from a suitable blank or sheet, and which when applied will give a maximum holding or anchoring effect.

The invention also aims to provide a form of tie which will be adapted for anchoring a surfacing layer of bricks, blocks or the like, to a frame structure as well as for tying together either juxtaposed or spaced inner and outer brick or block layers or courses.

With these and other objects in view, the invention includes the novel features of construction hereinafter described, the nature and scope of my invention being defined and ascertained by the claims appended hereto.

An embodiment of my invention is illustrated in the accompanying drawing, in which:

Figure 1 is a plan view of my improved tie.

Fig. 2 is a sectional view on line 2—2 of Fig. 1.

Fig. 3 is a similar view on line 3—3 of Fig. 1.

Figs. 4, 5 and 6 are perspective views illustrating my invention applied respectively in connection with a spaced two-course wall, a juxtaposed two-course wall, and a facing course secured to a boarded wall.

Fig. 7 is a plan view of a modified form.

Referring by reference characters to these drawings, and first to Figs. 1 to 3 inclusive, it will be seen that my improved tie comprises an elongated strip of sheet metal having an intermediate or main body portion 1 and marginal sinuous strands connected at intervals to the edges of the body portion. In the embodiment shown in these figures, the body portion preferably comprises a plain portion 1^a arranged intermediate of two corrugated portions 1^b, 1^c. These corrugated portions are preferably formed by

indenting the strip on transverse lines terminating short of the margins of the body portion so as to produce alternating depressions and elevations *b* leaving the edges of the body portion relatively straight, though in the stamping action they may be drawn into slightly sinuous lines.

The sinuous marginal strands are formed by providing the blank from which the tie is made with two rows of longitudinal slits to produce marginal strands 1^c which are connected at intervals to the edges of the body portion as indicated at *c*, and the intermediate portions of the strands are expanded outwardly away from the edges of the body portion to produce the sinuous effect, and at the same time the strands are preferably turned so that the metal of the strand at any given point lies in a plane disposed at an angle to the plane of the sheet and preferably substantially perpendicular thereto. I thus provide a tie which is composed of a corrugated body portion and expanded metal marginal portions and such a tie secures a maximum holding or anchoring effect in the mortar in which it is embedded.

Preferably one end portion of the tie is provided with nail holes as indicated at 1^d and where the tie is to be used for anchoring a brick or block facing course 2 to a wooden wall 3, the tie is bent into L shape to permit the perforated portion to be secured to the wall by nails as indicated at 4. As the outer bends *c'* of the corresponding sinuous strands are approximately in line with the center of the plain portion 1^a, the bend takes place along this transverse line and the tie strip bends readily without any distortion or buckling.

If desired, I may construct the tie as shown in Fig. 7, particularly when the tie is intended more particularly for uses such as exemplified in Figs. 4 and 6.

In this form the central plain portion 1^x of the strip is unprovided with marginal strands, the said strands 1^y being confined to and coextensive with the corrugated portions 1^z of the strip.

Having thus described my invention, what I claim is:

1. As an article of manufacture, a wall tie formed from a single piece of metal having an intermediate corrugated portion and marginal expanded metal portions.

2. A wall tie formed from a single strip

- of sheet metal having a corrugated intermediate portion and marginal portions bent at angles to the plane of the intermediate portion.
5. A wall tie formed from a single strip of sheet metal having a corrugated intermediate portion and marginal portions bent at angles to the plane of the intermediate portion, said marginal portions being in the 10 form of strands united at intervals with said intermediate portion.
4. A wall tie formed from a single piece of metal comprising an elongated strip, and a sinuous strand at an edge of the band 15 united therewith at intervals.
5. A wall tie formed from a single piece of metal, comprising an elongated strip, and

a sinuous strand at an edge of the band united therewith at intervals, said sinuous band being disposed at an angle to the plane 20 of the strip.

6. A wall tie formed from a single strip of metal, comprising an elongated body portion and sinuous marginal strands disposed in planes substantially perpendicular to the 25 body portion and united to the edges thereof at intervals.

7. A wall tie comprising a body portion having perforations and marginal sinuous strands disposed in planes substantially perpendicular to said body portion and united thereto at intervals.

In testimony whereof, I affix my signature,

LEWIS E. CURTIS.
